(57) **CLAIM**

The ornamental design for a measuring spoon, as shown and described.

DESCRIPTION

FIG. 1 is a top, side and rear perspective view of the first embodiment of a measuring spoon showing my new design;

FIG. 2 is a bottom, side and front perspective view thereof;

FIG. 3 is a top plan view thereof;

FIG. 4 is a bottom plan view thereof;

FIG. 5 is a left side elevation view thereof, the right side being a mirror image thereof;

FIG. 6 is a front elevation view thereof;

FIG. 7 is a rear elevation view thereof;

FIG. 8 is a top, side and rear perspective view of a second embodiment of a measuring spoon showing my new design;

FIG. 9 is a bottom, side and front perspective view thereof;

FIG. 10 is a top plan view thereof;

FIG. 11 is a bottom plan view thereof;

FIG. 12 is a left side elevation view thereof, the right side being a mirror image thereof;

FIG. 13 is a front elevation view thereof; and,

FIG. 14 is a rear elevation view thereof.
